Primary Examiner — Keli L Hill*Assistant Examiner* — Harold E Blackwell, II*(74) Attorney, Agent, or Firm* — Quickpatents, LLC; Kevin Prince(57) **CLAIM**

The ornamental design for a tool holding bracket, as shown and described.

DESCRIPTION

FIG. 1 is a perspective view of a tool holding bracket, showing my new design,

FIG. 2 is a front elevational view of FIG. 1;

FIG. 3 is a rear elevational view of FIG. 1;

FIG. 4 is a left-side elevational view of FIG. 1;

FIG. 5 is a right-side elevational view of FIG. 1;

FIG. 6 is a top plan view of FIG. 1; and,

FIG. 7 is a bottom plan view of FIG. 1.

The broken lines showing a bicycle wheel in FIG. 1 and the rack in FIGS. 1, 2 & 4-7, depict environmental matter and form no part of the claimed design. The remaining broken lines represent portions of the tool holding bracket that form no part of the claimed design.
